UNITED STATES PATENT OFFICE.

HARRY LAVINE, OF NEW YORK, N. Y.

SHOULDER-PAD.

SPECIFICATION forming part of Letters Patent No. 747,734, dated December 22, 1903.

Application filed June 18, 1903. Serial No. 162,058. (No model.)

To all whom it may concern:

Be it known that I, HARRY LAVINE, a citizen of the United States, and a resident of the city of New York, borough of Manhattan, in the county and State of New York, have invented a new and Improved Shoulder-Pad, of which the following is a full, clear, and exact description.

This invention relates to improvements in shoulder-pads for coats or like garments, an object being to provide a pad so constructed as to maintain a gradually-increasing thickness from one edge to the other, thus preventing any abrupt depressions in the shoulder portion of a coat or the like in which the pad may be placed.

I will describe a shoulder-pad embodying my invention and then point out the novel features in the appended claim.

Reference is to be had to the accompanying drawings, forming a part of this specification, in which similar characters of reference indicate corresponding parts in both the figures.

Figure 1 is a plan view of a shoulder-pad embodying my invention, and Fig. 2 is a section on the line $x-x$ of Fig. 1.

The shoulder-pad comprises outer layers 1 and 2 of suitable fabric, between which is placed a wadding 3, and preferably between the outer fabric 1 and the wadding a stiffening material—such, for instance, as haircloth 4—

is placed. The pad is crescent-shaped, or, in other words, has a convex edge 5 and a concave edge 6. At the convex edge the parts are secured together by three rows of stitching 7 8 9, the said rows of stitching gradually diminishing in tension from the convex edge toward the concave edge, and between the stitching 9 and the concave edge the parts are secured by bastings 10. By thus securing the parts together the pad has a gradually-increasing thickness from its convex to its concave edge.

Having thus described my invention, I claim as new and desire to secure by Letters Patent—

A shoulder-pad having a concave edge and a convex edge, the said pad comprising outer layers of fabric, a wadding between said outer layers, a stiffening material between one of the outer layers and the wadding, a plurality of rows of stitches at the convex edge, the said rows being of gradually-diminishing tension, and bastings between said stitchings and the concave edge.

In testimony whereof I have signed my name to this specification in the presence of two subscribing witnesses.

HARRY LAVINE.
